UNITED STATES PATENT OFFICE

HERBERT T. HERR, OF PHILADELPHIA, PENNSYLVANIA, ASSIGNOR TO WESTINGHOUSE ELECTRIC & MANUFACTURING COMPANY, A CORPORATION OF PENNSYLVANIA

CYLINDER MANIFOLD FOR INTERNAL-COMBUSTION ENGINES

Application filed January 11, 1929. Serial No. 331,810.

My invention relates to internal combustion engines and particularly to manifolds utilized for conveying fluid to or discharging fluid from a plurality of the engine cylinders, and it has for an object to provide apparatus of the character designated which shall be so arranged as to provide free and open communication with the ports in all of the engine cylinders and which shall embody ready means for detachably securing the manifold to the engine cylinders.

It has for a further object to provide an engine manifold which shall be relatively light in weight but which shall, at the same time, possess the required structural strength and which shall so engage the cylinders as to be effective to resist any engine working forces which may tend to displace the cylinders relative to each other.

These and other objects are effected by my invention, as will be apparent from the following description and claims taken in connection with the accompanying drawing, forming a part of this application, in which:

Fig. 1 is a plan view, in section, showing one form of manifold secured to a plurality of cylinders and arranged in accordance with my invention;

Fig. 2 is a view, in elevation, of the cylinders and manifolds shown in Fig. 1;

Fig. 3 is a view, in sectional elevation, taken through the manifold on the line III-III of Fig. 1;

Fig. 4 is a partial view, in sectional elevation, taken through the cylinder and manifold on the line IV-IV of Fig. 2;

Fig. 5 is a partial detail view, in sectional elevation, and showing the structure provided for attaching the manifold to the respective cylinders; and,

Fig. 6 is a detail plan view of the spring ring utilized in the assembly of the manifold upon each of the cylinders.

Referring now to the drawing, I show in Figs. 1 and 2 a plurality of cylinder structures 10 disposed in side-by-side relation. As shown, the cylinder structures are arranged in accordance with a form of engine disclosed in a copending application of mine entitled "Internal combustion engine" and

assigned to the Westinghouse Electric & Manufacturing Company. In the aforesaid application, the cylinder structures are arranged in polygonal sets and respective cylinder structures of each polygonal set are disposed in the manner illustrated in the present application. While the present invention is especially applicable to a cylinder structure arrangement such as disclosed in the aforesaid copending application, nevertheless it will be apparent from the following description that the present invention is also applicable to various other types of engines and arrangements of cylinder structures.

In Fig. 2, the cylinder structures illustrated are of the opposed piston type and are therefore provided with a plurality of circumferentially-spaced scavenging fluid or fuel mixture inlet ports 11, and circumferentially-spaced exhaust ports 13. Associated with the inlet ports 11 is a manifold 14 for supplying the fluid thereto. While, in the present embodiment, my improved form of manifold is specifically utilized for supplying scavenging fluid to the engine cylinder structures, nevertheless it is obvious that it is equally well adapted for conveying the burnt gases from the cylinder exhaust ports or for conveying any other media to or from a plurality of cylinders.

The manifold 14 is preferably so arranged that it completely surrounds the scavenging air inlet ports 11 provided in the respective cylinder structures in order to provide free and uninterrupted passage of the scavenging fluid into the interior of all the cylinders. Preferably, as shown, the scavenging fluid inlet ports in the respective cylinder structures are arranged somewhat tangentially so that the air entering the engine cylinders is given a whirling or rotary motion in order to provide thorough scavenging.

The manifold 10 comprises upper and lower walls 15 and 16 and circular end portions 17 and 18. A scavenging fluid inlet 19 is located at one end of the manifold while the other open end 20 of the manifold is covered by a plate 21, this plate, as shown in the aforesaid copending application, forming a portion of the engine gear case. Preferably,

the manifold is composed of some sheet material such as, for example, stainless steel, which is relatively light in weight and which will not rust or corrode because of contact 5 with any moisture which may be contained in the fluid it conveys.

In order that the manifold may possess the required structural strength and rigidity, I provide interiorly of the manifold a plurality of stress members or stays 22 joined at their respective ends to the upper and lower walls 15 and 16, as at 23 and 24, respectively. Preferably, these stays are composed of some material such as, for example, piano wire, 10 which possesses an extraordinary tensile strength so that the diameter of the stays, as well as their weight, is reduced to a minimum and at the same time very little resistance is offered to the passage of the scavenging fluid through the manifold. The ends 15 of the stays 22 may be secured to the walls of the manifold in any approved manner. However, they preferably extend through 20 the walls of the manifold and are secured to the exterior surfaces thereof as by soldering.

In order to detachably secure the manifold to its associated cylinder structures, I provide on each cylinder structure, as shown particularly in Figs. 4 and 5, screw-threaded 30 manifold flanges 25 and 26. As shown, the cylinder structure is composed, essentially, of a cylinder 27 and a cylinder jacket sleeve 28, the annular space intervening between the cylinder and the jacket sleeve forming a cylinder cooling jacket. Although the flanges 35 25 and 26 are located upon the exterior surfaces of the jacket sleeve, nevertheless, it is obvious that these flanges may be provided directly upon the cylinder in such installations where no cooling jacket is included.

The jacket flange 24 is provided with a projecting portion 29 against which one of the walls of the manifold is arranged to abut and it is also provided with a locking ring 45 30 for clamping the manifold against the projecting portion 29. It will be further noted by referring to Fig. 5 that the cylinder opening 31 in the manifold is of greater diameter than the opening 32, the former opening being sufficiently large to permit the manifold 50 to be freely telescoped or passed over the projecting portion 29 of the jacket flange 25. The projecting flange 26 is therefore provided with a spring ring 33 which, as shown 55 in Fig. 6, is diagonally split, as at 34, and which is so formed that it may be forced open and over the jacket flange 26 and, upon release, will enter a suitable groove 35 provided in the jacket flange 26 and form 60 an abutment for the wall of the manifold. A locking ring 36 is therefore provided, which locking ring engages the threads provided on the flange ring 26 and is arranged to secure the wall of the 65 manifold against the spring ring 33. Pref-

erably, the cylinder 27 is provided with projecting flange portions 37 and 38 located in the vicinity of the jacket flanges 25 and 26 and engaging the jacket sleeve so that the cylinder 27 cooperates with the jacket sleeve 70 to retain the manifold in place.

Referring now to the method of attaching the respective cylinder structures to the manifold, it is noted that the spring ring 33 is first inserted within the manifold. Preferably, the intermediate cylinder structure is inserted first and this cylinder structure is projected into the manifold, the opening 31 being sufficiently large to permit the projecting portion 29 of the manifold flange 25 to pass freely therethrough. The spring ring 33 is then opened and passed over the exterior surface of the cylinder structure after which the cylinder structure is further inserted into the manifold until the projecting portion 29 of the flange 25 abuts against the manifold wall after which the locking ring 30 is secured in place from exteriorly of the manifold.

The spring ring 33 is then again opened and is sprung into the groove 35, whereupon the locking ring 36 is threaded upon the flange ring 26 until its associated wall of the cylinder is fixedly retained in place, the spring ring 33 serving as an abutment for 90 this purpose.

Thereafter, the end cylinder structures are inserted and secured in the manifold in like manner, the inlet opening 19 and the oppositely-disposed open end 20 providing the necessary access to the interior of the manifold. The cylinder structures 10, together with the manifold 14 assembled thereon, may then be inserted, as a unit, in the engine structure.

From the foregoing, it will be apparent that I have devised a form of manifold which is extremely light in weight, and which may be readily attached to or detached from the engine cylinders, the attaching means being also made relatively light in weight. By providing stays of the character shown at 22, the manifold is given the required structural strength with very little increase in the weight thereof. It will be further noted that by providing the flanges 37 and 38 upon the cylinder, the weight of the manifold is not imposed entirely upon the relatively light structure of the cylinder jacket sleeve but is transmitted to the cylinder itself. I have found such a form of manifold to be especially adapted for use in engines of the opposed piston or square or polygon types wherein the manifold serves to tie the cylinders together, and therefore serves as a stress member to resist engine working forces tending to distort the engine and to displace the cylinders relative to each other.

While I have shown my invention in but one form, it will be obvious to those skilled 130

in the art that it is not so limited, but is susceptible of various changes and modifications, without departing from the spirit thereof, and I desire, therefore, that only such limitations shall be placed thereupon as are imposed by the prior art or as are specifically set forth in the appended claims.

What I claim is:

1. In an internal combustion engine, the combination with a plurality of opposed piston cylinders having inlet ports for the admission of scavenging fluid to the respective cylinders and exhaust ports for the discharge of exhaust gases from the respective cylinders, of a manifold surrounding the cylinders and communicating with the scavenging ports thereof, and means for detachably securing oppositely-disposed wall portions of said manifold to the cylinders.

10 2. In an engine, the combination of a plurality of cylinder structures having ports provided therein, a manifold formed separately from the cylinders, surrounding the cylinders and communicating with the ports thereof, and detachable means disposed circumferentially about each of the cylinders for supporting the manifold therefrom.

20 3. In an engine, the combination of a plurality of cylinder structures having ports provided therein, a manifold communicating with the ports of the cylinder structures and having oppositely-disposed wall portions abutting against the cylinder structures, and detachable means disposed circumferentially about each of the cylinder structures for securing said abutting wall portions thereto.

4. In an engine, the combination of a manifold having oppositely disposed wall portions and cylinder openings provided in said wall portions, a plurality of cylinder structures projecting through the openings in the wall portions, said cylinder structures having ports communicating with the interior of the manifold, and detachable means associated with each of the cylinder openings for supporting the manifold from the cylinder structures.

5. In an engine, the combination of a manifold having oppositely disposed wall portions and cylinder openings provided in said wall portions, a plurality of cylinder structures projecting through the openings in the wall portions, said cylinder structures having circumferentially spaced ports communicating with the interior of the manifold, and independent fluid-tight means associated with each cylinder opening and detachably supporting the manifold from the cylinder structures.

6. In an engine, the combination of a plurality of cylinder structures having ports provided therein, a projecting flange portion disposed circumferentially about each of the cylinder structures, a manifold communicating with and surrounding the ports of the

cylinder structures, and means for detachably supporting the manifold from the projecting flange portions provided on the cylinder structures.

7. In an engine, the combination of a plurality of cylinder structures having ports provided therein, a circumferentially extending projecting flange portion provided on each of the cylinder structures, a manifold for the cylinders and communicating with the ports thereof, and detachable means disposed circumferentially about the respective cylinders for securing oppositely-disposed wall portions of the manifold to the projecting flange portions thereof.

8. In an engine, the combination of a manifold having oppositely disposed wall portions provided with cylinder openings, cylinder structures extending through the openings in the manifold and having ports communicating with the interior of the manifold, and detachable means disposed circumferentially about each of the cylinders and cooperating with each of said manifold wall portions for securing the manifold to the cylinder structures.

9. In an engine, the combination of a manifold having oppositely disposed wall portions provided with cylinder openings, cylinder structures extending through the openings in the manifold and having ports connecting with the interior of the manifold, projecting flanges provided on each of the cylinder structures adjacent to said manifold wall portions, and means for securing the respective cylinder structure flange portions to their associated manifold wall portions.

10. In an engine, the combination of a plurality of cylinder structures having ports provided therein, said cylinder structures being disposed in side-by-side relation, a manifold telescoped about a portion of each of the cylinder structures and communicating with the ports thereof, and detachable means for securing the outer periphery of each cylinder structure to the walls of the manifold disposed thereabout.

11. In an engine, the combination of a manifold having oppositely disposed first and second wall portions provided with cylinder openings, the opening in the first manifold wall portion being larger than the opening in the second manifold wall portion, a cylinder structure having a port communicating with the interior of the manifold, a flange portion provided on the cylinder structure and formed so as to be insertable through the large opening in the first manifold wall portion and to engage the second manifold wall portion, means for securing said flange portion to the second manifold wall portion, and means for securing the first manifold wall portion to the cylinder structure.

12. In an engine, the combination of a

- manifold having oppositely disposed first and second wall portions provided with cylinder openings, the opening in the first manifold wall portion being larger than the opening in the second manifold wall portion, a cylinder structure having a port communicating with the interior of the manifold, a circumferentially extending flange portion provided on the cylinder structure and formed so as to be insertable through the large opening in the first manifold wall portion and to engage the second manifold wall portion, a locking member engaging the exterior of the cylinder structure and disposed exteriorly of the manifold for retaining the flange portion of the cylinder structure and the second manifold wall portion in fixed engagement, and means for securing the first manifold wall portion to the cylinder structure.
13. In an engine, the combination of a manifold having oppositely disposed first and second wall portions provided with cylinder openings, the opening in the first manifold wall portion being larger than the opening in the second manifold wall portion, a cylinder structure having a port communicating with the interior of the manifold, a circumferentially extending flange portion provided on the cylinder structure and formed so as to be insertable through the large opening in the first manifold wall portion and to engage the second manifold wall portion, means for securing said projecting flange portion to the second manifold wall portion, detachable means disposed interiorly of the manifold and engaging the cylinder structure for retaining the first manifold wall portion, and means disposed exteriorly of the manifold for retaining said detachable means and the first manifold wall portion in fixed engagement.
14. In an engine, the combination of a manifold having oppositely disposed first and second wall portions provided with cylinder openings, the opening in the first manifold wall portion being larger than the opening in the second manifold wall portion, a cylinder structure having a port communicating with the interior of the manifold, a circumferentially extending flange portion provided on the cylinder structure and formed so as to be insertable through the large opening in the first manifold wall portion and to engage the second manifold wall portion, means for securing said projecting flange portion to the second manifold wall portion, a detachable spring ring disposed interiorly of the manifold and engaging the cylinder structure for retaining the first manifold wall portion, and a locking ring disposed exteriorly of the manifold and cooperating with the spring ring for securing the first manifold wall portion to the cylinder structure.
15. In an engine, the combination of a manifold having oppositely disposed first

and second wall portions provided with cylinder openings, the opening in the first manifold wall portion being larger than the opening in the second manifold wall portion, a cylinder structure having a port communicating with the interior of the manifold, a flange portion provided on the cylinder structure and formed so as to be insertable through the opening in the first manifold wall portion and to engage the second manifold wall portion, a locking ring disposed exteriorly of the manifold and cooperating with the flange portion of the cylinder structure to secure the second manifold wall portion to the cylinder structure, a spring ring disposed within the manifold adjacent to the first manifold wall portion, said spring ring being insertable in a retaining recess provided in the cylinder structure, and a locking member disposed exteriorly of the manifold and cooperating with the spring ring for securing the first manifold wall portion to the cylinder structure.

16. In an internal combustion engine, the combination of a cylinder structure having a port provided therein and embodying a cylinder and a jacket sleeve spaced about the cylinder and defining therewith a cooling jacket, a manifold arranged circumferentially about the jacket sleeve and communicating with the port in the cylinder structure, means for detachably securing the manifold to the jacket sleeve, and means provided on the cylinder within the cooling jacket and cooperating with said securing means for supporting the manifold from the cylinder.

17. In an engine, the combination of a manifold embodying oppositely-disposed wall portions having cylinder openings provided therein, a plurality of cylinder structures extending through the openings in the manifold and having ports communicating with the interior of the manifold, each of said cylinder structures embodying a cylinder and a jacket sleeve spaced exteriorly about the cylinder and defining therewith a cylinder cooling jacket, detachable means extending circumferentially about each of the cylinder jackets and cooperating with each of said manifold wall portions for securing the manifold to the cylinder jacket sleeve, and reinforcing members provided on each of the cylinders in the vicinity of said manifold securing means and cooperating with the jacket sleeve to support the manifold.

18. A manifold for the cylinders of an internal combustion engine comprising a manifold body having oppositely-disposed flat wall portions and a plurality of reinforcing wires disposed within the manifold body and extending between and secured to said oppositely-disposed wall portions.

19. A manifold for the cylinders of an internal combustion engine comprising a manifold body having oppositely-disposed wall

portions and a plurality of spaced, reinforcing wires disposed within the manifold body and extending between and through said oppositely-disposed wall portions, and means 5 for securing the respective end portions of said reinforcing wires to the exterior surfaces of the oppositely-disposed wall portions.

20. A manifold for the cylinders of an internal combustion engine comprising a body 10 portion formed of sheet material and having oppositely-disposed flat wall portions and oppositely-disposed curved wall portions, and a plurality of reinforcing wires disposed within the manifold body and extending be- 15 tween and secured to said oppositely-disposed flat wall portions.

In testimony whereof, I have hereunto subscribed my name this 3rd day of January, 1929.

20

HERBERT T. HERR.
